UNITED STATES PATENT OFFICE.

CHARLES H. PHELPS, OF CUYAHOGA FALLS, OHIO, ASSIGNOR TO EDWIN LEE BROWN AND EDWIN F. BROWN, OF CHICAGO, ILLINOIS.

SEAT FOR BICYCLES.

SPECIFICATION forming part of Letters Patent No. 408,743, dated August 13, 1889.

Application filed June 5, 1889. Serial No. 318,170. (No model.)

To all whom it may concern:

Be it known that I, CHARLES H. PHELPS, of Cuyahoga Falls, in the county of Summit and State of Ohio, have invented a certain 5 new and useful Improvement in Seats for Cycles, of which the following is a specification, reference being made to the accompanying drawings, in which—

Figure 1 is a side view of a cycle-seat embodying my improvement. Fig. 2 is a bottom plan view of the same. Fig. 3 is a detail top plan of the spring-seat of the same; and Fig. 4 is an end view of Fig. 3, partly in section, through one of the screw-clips or eyebolts 15 and connections.

My invention relates to the saddles commonly used on bicycles and analogous vehicles.

It consists of a saddle in combination with 20 spiral springs having the general contour of semi-elliptic springs. In other words, it consists of a knotted hammock-spring.

In the drawings, which represent the best known embodiment of my invention, A represents the leathern saddle, A' being the reinforcing strip of leather around the usual central slot, the margin of which is indicated by a. This saddle is supported in front by the upper ends of a pair of obliquely-spiral 25 springs b b, uniting in a socket c, cast upon the stretching-frame or "front hook" C, to which the leathern saddle is riveted at c'. The rear end of the leathern saddle is similarly supported by a pair of similar springs 30 d d, which, however, are secured in separate sockets e e to a larger stretching-frame—namely, the hind bow or cantle E, to which the leathern saddle is riveted at e'. These stretching-frames have no strut to hold them 35 apart, the springs performing this duty as well as supporting the saddle.

The springs b b are united at their lower ends by a cross-piece b', both of which springs and the cross-piece being (all three) formed 40 by bending a single steel wire B of round cross-section. Similarly the springs d d and their cross-piece d' are formed of a similar single wire D. The wires B and D below the spiral part are secured to a spring-seat F by 45 means of screw-clips or eyebolts G and their nuts g, the spring-seat being hollowed out at 50

the corners for the reception of the eyebolts. The top or face of the spring-seat is also provided with two parallel grooves f f to receive the wires B and D and keep them secured 55 against lateral displacement at their junction with the spring-seat, the eyebolt, in conjunction with the spring-seat, preventing vertical displacement of the wires. The spring-seat is sufficiently hollowed out at the corners 60 (for the reception of the heads of the eyebolts) to let the wires B and D down to the bottoms of the ends of the grooves whether the cross-pieces (which, being themselves entirely out of the grooves, obviously keep the 65 adjacent uncoiled ends of the springs b b and d d above the grooves) may be placed at a greater or less distance from their respective screw-clips. This construction obviously affords a convenient means of adjusting the 70 tension in the saddle itself, and, in fact, the tension of the saddle and springs when combined and considered as a whole, the tension being increased by setting the cross-pieces nearer the screw-clips, which act as set- 75 screws. As shown, the heads of the eyebolts are at the bottoms of their recesses, because the cross-pieces are supposed to be set at their farthest adjustment from their respective eyebolts.

The spring-seat is hollowed out at f' f' to receive the seat-rod H (shown in Fig. 4 only) of the bicycle or other vehicle, the set-screw L securing the cycle-seat in any desired location thereon. The spring-seat is also hollowed out above the seat-rod to dispense with unnecessary material and make a skeleton casting thereof.

I have used the term "obliquely spiral" in describing the springs to indicate that (neglecting the curvature of the axis of the spiral corresponding with the general contour of the spring as a whole) the angle which the radius of the spiral makes with its axis is other than a right angle. In the springs shown the obliquity of this angle is so great and the pitch of the spirals so small that successive coils are contiguous, this construction slightly stiffening the springs against the lateral vibration.

The spring-seat is located at some distance from each end of the saddle and the axis of

the spiral is practically co-extensive with the length of the saddle and not confined to a particular point in the length of the same. By this construction a desirable forward and backward as well as vertical vibration of the saddle is obtained; and in addition to these motions there is a torsional vibration (in the horizontal plane) around the spring-seat to accommodate the alternate propelling motions of the legs of the rider, which torsional flexibility is obviously impaired when the spiral is bunched together in one spot under the end of the saddle.

The springs *b* and *d*, corresponding with each other—that is, on the same side of the spring-seat—in connection with the spring-seat obviously form, when the whole effect is considered, a universally-flexible semi-elliptic spring.

Having thus fully and particularly described the best known embodiment of my invention, what I claim as the invention itself, and desire to secure by Letters Patent, is—

1. In a seat for cycles, the combination of 20 a saddle and spiral springs having the general contour of semi-elliptic springs, substantially as set forth.

2. In a seat for cycles, the combination of 25 a saddle of flexible material, the spiral springs 30 having the general contour of semi-elliptic springs, and a spring-seat provided with adjustable clips, substantially as set forth.

CHARLES H. PHELPS.
